TIE CLASP

Hugh A. Robertson, Portland, Oreg.

Application October 8, 1954, Serial No. 461,073

1 Claim. (Cl. 24—49)

This invention relates to fastening devices and, more specifically, relates to a tie clasp engageable with a man's shirt and tie for holding the tie in a desired position against the shirt.

Objects of the invention are to provide a tie clasp having improved means to engage a portion of a man's shirt for holding a tie in position relative to the shirt and for preventing accidental displacement of the clasp therefrom; to provide a tie clasp having improved retaining means which positively engages a portion of a shirt but does not fold or wrinkle or otherwise appreciably damage the shirt; to provide a tie clasp which is easily attached and detached, when desired, and to provide a tie clasp which is simple in structure and inexpensive to manufacture.

The objects of the invention are accomplished by a clasp structure having a U-shaped body member which receives portions of a shirt and tie. A clamping plate is hingedly mounted on the body member and has piercing members which pass through apertures in the body member to engage portions of a shirt and tie received in the body member to hold the tie to the shirt. The invention will be better understood and additional objects and advantages will become apparent with reference to the accompanying drawings which illustrate a preferred embodiment. Various changes may be made in the construction and arrangement of parts within the scope of the appended claim without departing from the spirit of the invention.

In the drawings:

Figure 1 is a perspective view of a man with the present tie clasp locked on a portion of his shirt and holding his tie against the front of his shirt;

Figure 2 is a plan view of the clasp taken on the line 2—2 of Figure 1, the shirt and tie material being shown in phantom;

Figure 3 is a plan view with the hinged clamping plate in open position, a portion of the clasp frame being broken away to show the apertures in the frame member for receiving the piercing members; and

Figure 4 is a perspective view of the clasp, also showing the clamping plate in open position.

Referring in detail to the drawings, it will be seen that the tie clasp is formed from two parts 10 and 11. The part 10 comprises a pair of legs 14 and 15 joined at one end 16 to form a U-shaped body member adapted to receive therein a portion of a man's shirt 17 and tie 18. End portion 16 inclines inwardly toward leg 15 whereby the corner 19 between end 16 and leg 14 protrudes outwardly beyond the corner formed between end 16 and leg 15. The angle at corner 19 is therefore an acute angle of somewhat less than 90°.

Leg 14 of the body 10 has a pair of longitudinally spaced apertures 20 and has a hinge portion 21 on its free end for connection to the part 11 of the clasp. Part 11 comprises a clamping plate and is provided with a pair of piercing members comprising needle-shaped

2

prongs 23 located in predetermined spaced relation so as to pass through apertures 20 in leg 14 when the plate 11 is moved on its hinge to a closed position in close proximity with the U-shaped body, as shown in Figure 2. The 5 free or outer end of plate 11 is curved inwardly at 24 to form a spring catch 25 and is curved outwardly at 26 to form a finger grip 27 for operating the spring catch. To lock the plate 11 against the body 10, it is rotated to a position in close proximity with the body, 10 and then, with an additional pressure thereon, spring catch 25 will snap over the protruding corner 19 between end 16 and the leg 14. Plate 11 will remain in its locked position until released by outward pressure on the finger grip 27.

15 Leg 15 of the frame 10 is preferably a fraction of an inch longer than leg 14 so as to protrude slightly beyond the hinge 21. This extended end portion is useful for guiding the frame 10 into engagement with the shirt and tie when the clip is to be put in place. The space between the legs 14 and 15 forms a holder of a width such that one thickness of a shirt, or its front panel, and two thicknesses of a tie, will readily fit therein for easy attachment and detachment of the clasp from said shirt and tie. Furthermore, the interior surfaces of the frame 10 20 for receiving the shirt and tie are flat and uninterrupted, and devoid of any obstructions, recesses, projections or the like which may be instrumental in folding or creasing the shirt and tie material.

25 To mount the clasp on a shirt and tie, the clamping plate 11 is pivoted outwardly on its hinge to the position shown in Figures 3 and 4. The clasp is turned so that the clamping plate 11 faces the wearer's body, and then the clasp is moved into engagement with the shirt and tie. When a desired position is obtained, clamping plate 11 is pivoted to a locked position, as shown in Figure 2. Prongs 23 are preferably of a length sufficient to span the gap between legs 14 and 15, as shown, so that they pierce the thickness of the shirt, the thickness of the narrow underneath end of the tie, which is the center thickness of material in Figure 2, and only partially the thickness of the wide outermost end of the tie. The prongs are very slender to avoid making holes of noticeable size in the shirt. After the clasp is removed, the holes are too small to be seen and too small to damage 30 the shirt.

35 An important advantage of the invention is that the clasp, when locked in position, cannot accidentally become displaced from the shirt. In addition, with the provision of the pair of spaced prongs 23, the clasp cannot pivot, but will remain in its initial set position. Although the wide outermost portion of the tie is firmly held in a set position by the prongs 23, it is nevertheless not damaged due to only partial penetration thereof by the prongs.

40 Having now described my invention and in what manner the same may be used, what I claim as new and desire to protect by Letters Patent is:

45 A tie clasp for securing a necktie to a shirt front, comprising a flat strip of material formed into a U-shaped body member, said member having a shirt engaging leg adapted to be disposed inside the shirt and a tie engaging leg joined by an end portion and two angles intermediate the ends of the strip, said tie engaging leg being adapted to overlie the front of the tie, the angle between 50 said shirt engaging leg and end portion being less than 90° to form a catch detent, said shirt engaging leg having a pair of longitudinally spaced apertures, a flat-backed clamping plate pivotally mounted on said shirt engaging 55 leg at one end of said strip and adapted to lie flat against the back surface of said shirt engaging leg, a spring catch 60 65 70

on said clamping plate engageable over the corner of said angle detent to lock said clamping plate against said back surface of said shirt engaging leg to bear against the body of the wearer, and a pair of spaced needle-shaped prongs on said clamping plate in positions to pass through said apertures, said prongs being of a predetermined length insufficient to span the gap between said legs in order to pierce the shirt and only a portion of the thickness of a necktie between said legs without piercing the front surface of the necktie.
